UNITED STATES PATENT OFFICE

ALICE L. BREWER, OF EAST HARTFORD, CONNECTICUT

KEYHOLE GUARD

Application filed January 15, 1931. Serial No. 508,958.

This invention relates to certain new and useful improvements in keyhole guards. The primary object of the invention is to provide a guard or attachment for keyholes of door locks and operates in a manner to prevent removal of a key from a lock casing, it being frequently found desirable to leave a key in a door lock and in many instances such keys become lost by being taken from the lock casing or falling therefrom during opening and closing movements of a door.

The invention also embodies a safety feature which prevents removal of the key from the lock casing by attempting to eject the same therefrom by the insertion of another key or tool, the invention also being serviceable in that the keyhole opening is completely closed when a key is inserted in the locking casing and the guard is in position in the key slot or hole.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a front elevational view of the face plate of a lock in which the keyhole is equipped with a guard attachment;

Figure 2 is a cross-sectional view taken on line 2—2 of Figure 1;

Figure 3 is a vertical cross-sectional view showing a key in position in the opening of the face plate of the lock and the guard attachment extending into the opening preventing removal of the key;

Figure 4 is a top plan view of the side attachment;

Figure 5 is a bottom plan view of the attachment;

Figure 6 is a rear elevational view with the wedge member of the attachment partially removed from the attachment casing and in position to permit compression of the attachment casing for mounting in a keyhole opening;

Figure 7 is a longitudinal sectional view of the guard attachment;

Figure 8 is a perspective view of a modified form of the invention, showing the guard attachment of flap tapering formation;

Figure 9 is a top plan view of the device shown in Figure 8;

Figure 10 is a front elevational view of the attachment shown in Figures 8 and 9 with the wedge member partly removed from the casing;

Figure 11 is a front elevational view of another form of guard attachment;

Figure 12 is an edge elevational view of the device shown in Figure 11;

Figure 13 is a rear elevational view of the device shown in Figures 11 and 12; and

Figure 14 is a top plan view of the plate of the attachment shown in Figures 11 to 13.

As shown in Figures 1 to 3, the reference numeral 1 designates the face plate of a door lock having a fancifully bordered opening 2 therein for the passage of a knob spindle and a key hole of the usual form being circular as at 3 at its upper end and having parallel walls 4 to the vertical slot portion of the keyhole as shown in Figure 2. In the form of keyhole guard attachment shown in Figures 1 to 7, the reference numeral 5 designates a tapering casing open at both ends and cut away longitudinally thereof at one side with the edge walls of the cut away portion directed outwardly as at 6 in parallel relation to each other with the outer terminal edges thereof bent outwardly at right angles as at 7 constituting retaining lugs for use in a manner presently to be described. A wedge 8 of shell formation is slidably mounted within the casing 5 and has one side thereof flattened as at 9 registering with the cut away side of the casing so that the device may assume a position adjacent the face plate 1 of the door lock as illustrated in Figures 3 and 6. A longitudinally extending slot 10 is provided in the casing 5 opposite the cut away side thereof and through which slot a pin 11 carried by the smaller end of the wedge-shaped member 8 extends, for coupling the two parts together.

In the use of the guard attachment, the key K has its shank thereof extending through the circular portion 3 of the keyhole 100

with the key ward positioned for engagement with the lock mechanism. The guard attachment is then inserted in the keyhole, application thereof being accomplished by first 5 shifting the wedge member 8 exteriorly of the casing 5 in the position shown in Figure 6 and at which time the sides of the cut away portion of the casing 5 may be moved toward each other so that the lugs 7 will be permitted 10 to pass between the parallel side edges 4 of the key hole slot and assume the position shown in Figure 3. At this time, the wedge member 8 is moved upwardly into the casing 5 and completely filling the same as illustrated, accidental displacement of the guard 15 attachment is prevented, the key hole completely closed and removal of the key K prevented, either accidentally or by a person trying to force the same from the key lock by 20 the insertion of another key at the opposite side of the door or by use of an implement of any character, the keyhole being completely closed by the guard attachment as will at once be apparent from an inspection of Figures 1 to 3.

In the form of the invention shown in Figures 8 to 10, the casing 5a of the guard attachment is of tapering and flattened form, the open side thereof being provided with 30 retaining lugs 7a while the wedge member 8a associated with the casing 5a is in the form of a tapering plate that carries a pin 11a guided in the slot 10a in the casing 5a as clearly shown in Figure 10, the wedge plate 35 8a when moved into the casing restraining movement of the lugs 7a toward each other.

Another form of the invention is shown in Figures 11 to 14, the key hole guard attachment comprising a wedge shaped plate 15 40 provided with a lateral extension 16 at one end thereof with outwardly directed lugs 17 at the outer ends of the extension. A pair of spring arms 18 are attached to the plate 15 as at 19 on the side thereof carrying the neck 45 and lugs 16 and 17, the lower ends of the spring arms, each carrying an outwardly directed lug 20. A pin 21 is journaled in the plate 15 and carries a cross head 22 at one end thereof disposed between the free ends 50 of the spring arms 18, the end of the pin projecting at the opposite side of the plate 15 being provided with an operating handle 23 having a button projection 24 receivable in indentations 25 for holding the lever 23 55 and cross head 22 in adjusted positions. The lugs 17 upon the upper end of the plate 15 and the lugs 20 upon the lower ends of the spring arms 18 are insertible through the keyhole 3-4 and upon operating the lever 23, the cross heads 22 upon the pin 21 separates the lugs 20 to move them into engagement with the rear sides of the edges of the keyhole walls 4, thus retaining the guard attachment in position in the keyhole.

60 65 From the above detailed description of the

invention, it is believed that the construction and operation thereof will at once be apparent and while there are herein shown and described the preferred embodiments of the invention it is nevertheless to be understood that minor changes may be made without departing from the spirit and scope of the invention as claimed.

I claim:—

1. A guard attachment for keyholes comprising a tubular casing longitudinally split on one side, an outwardly directed extension at each side edge of the split portion, an outwardly directed lug at the outer end of each extension to be engaged with the edge walls of a keyhole, and a wedge member in the casing to prevent movement of the lugs toward each other.

2. A guard attachment for keyholes comprising a tubular casing longitudinally split on one side, an outwardly directed extension at each side edge of the split portion, an outwardly directed lug at the outer end of each extension to be engaged with the edge walls of a keyhole, a wedge member in the casing to prevent movement of the lugs toward each other, a pin and slot connection between the casing and wedge member, and the inner side of the wedge member being flattened for close contact with a lock plate.

In testimony whereof I affix my signature.
ALICE L. BREWER.
